ALARM CLOCK

Christian E. Sholden, Minneapolis, Minn.

Application May 22, 1933, Serial No. 672,185

7 Claims. (Cl. 58—19)

My invention relates to alarm clocks and has for an object to provide a clock by means of which both an alarm and a signal may be given.

Another object of the invention resides in providing a clock in which the signal may be first given and the alarm subsequently given.

A still further object of the invention resides in constructing the clock with a single trip mechanism and in utilizing said trip mechanism for operating both the alarm and the signal.

Another object of the invention resides in utilizing an electrical alarm and an electrical signal requiring separate circuits and in further employing separate switches operated by the trip mechanism for actuating said circuits to procure operation of the alarm and signal.

A feature of the invention resides in constructing the trip mechanism with a staff having a member fixed relative thereto and having a member rotatable about the axis of said staff and slidable toward said fixed member and in further constructing one of said members with an abutment having two notches therein of different depth and in constructing the other of said members with a finger adapted to ride against said abutment and to enter either of said notches.

Other objects of the invention reside in the novel combination and arrangement of parts and in the details of construction hereinafter illustrated and/or described.

In the drawing:

Fig. 1 is a side elevational view of a portion of a clock showing my invention applied thereto.

Fig. 2 is a view similar to Fig. 1 with certain of the parts removed and showing other parts in altered position.

Fig. 3 is a fragmentary plan view of the structure shown in Fig. 1.

Fig. 4 is a wiring diagram of my invention.

In the use of alarm clocks highly unsatisfactory results occur. In some cases the alarm startles the slumberer so that an appreciable shock is undergone. In other instances the alarm fails to awaken. With my invention a signal in the form of a light is first given which serves to awaken a light sleeper and in the event that the same is insufficient, an alarm is subsequently sounded. The construction by means of which these results are accomplished will now be described in detail.

For the purpose of illustrating my invention, I have shown a part of an alarm clock which is indicated in its entirety by the reference character A. It can readily be comprehended that the

clock proper forms no particular feature of the invention and that the invention may be applied to any type of clock. For this reason the parts of the alarm clock not intimately associated with the invention have not been shown. The clock illustrated comprises a frame 10 which consists of two bearing plates 11 and 12 held in spaced relation with respect to one another by suitable posts 13. These posts may be riveted to the plate 12 as indicated at 14 and are formed with threaded studs 15 which pass through the plate 11. Nuts 16 screwed upon these studs hold the plate 11 properly attached to the frame. The various staffs of the clock which carry the pinion and gear wheels and escapement thereon and in case of an electrical clock, the motor parts, are mounted between the two bearing plates 11 and 12 and journaled through bearings formed therein or through jewels or in any suitable manner. As previously stated the majority of these parts forming no particular feature of the invention have not been shown. The particular clock illustrated is an electric clock and consists of a center staff 17 which passes through the two plates 10 and 11 and is journaled therein. This shaft carries a gear 18 through which motive power is directed to the said staff. The staff 17 in this particular clock is used to carry the second hand which has not been shown. Rotatably mounted upon the staff 17 and externally of the plate 11 is a gear assembly 19 which is mounted on a sleeve 20. Sleeve 20 supports the minute hand of the clock and comprises the usual chuck pinion 21 and the minute hand gear wheel 22. Power is transmitted from the gear wheel 18 to the gear wheel 22 through suitable reduction gearing which has not been shown in the drawing so that the sleeve 20 travels at the proper rate of speed. The chuck pinion 21 meshes with the motion gear wheel 23 of the clock which is provided with a motion pinion 24. This pinion meshes with the hour gear wheel 25 which is mounted upon another sleeve 26 rotatable upon the protruding end of the sleeve 20. The hour sleeve 26 has attached to it a gear wheel 27 by means of which the alarm trip mechanism which has been indicated in its entirety by the reference numeral 28 is operated. This construction will now be described in detail.

The trip mechanism includes a staff 29 which passes through the two plates 11 and 12. This staff is directly journaled in the plate 12 and indirectly journaled for rotation in the plate 11 in a manner to be hereinafter described. The

staff 29 serves to set the alarm pointer or hand and in normal operation of the clock, is stationary with respect to the frame 10. Upon the staff 29 and adjacent the plate 12 is a collar 30 which is fixed relative to said shaft in any suitable manner. This collar carries a head 31 somewhat larger in diameter than the collar proper, which serves a purpose to be presently described in detail. The collar 30 abuts against the inner surface of the plate 12. Upon the staff 29 is mounted another collar 32 which is spaced from the outer surface of the plate 12. Between this collar and the said plate is disposed a spring washer 33 which provides a friction between the staff 29 and frame 10 by means of which the staff is normally held stationary and through which the said staff may be rotated when it is desired to set the pointer or hand which indicates the time when the trip mechanism is tripped. For the purpose of rotating the staff 29 an alarm set 34 is employed which is screwed or otherwise secured upon the end of said staff.

Slidably and rotatably mounted upon the staff 29 between the two plates 11 and 12 is a trip member 35. This member consists of a hub 36 formed with a flange 37 projecting outwardly therefrom. On the hub 36 is secured a disk 38 constructed of some suitable electrical insulating material. The member 35 is driven through a sleeve 39 which is rotatably mounted upon the staff 29 and which is journaled in a bearing formed in the bearing plate 11. The sleeve 39 is provided at its outer end with a gear wheel 40 which meshes with the gear wheel 21 carried by the hour sleeve 26 and is further formed at its inner end with a longitudinal slot 41 forming part of a jaw coupling 42 by means of which the member 35 may be rotated. The hub 36 of said member is constructed with a tongue 43 which enters the slot 41, the same operating in the manner of a spline whereby the said member 36 may be rotated and still be permitted to slide longitudinally of the axis of a staff 29. To hold the sleeve 39 in proper position upon the staff 29 the same is reduced in diameter as designated at 44 where the same passes through the plate 11. The hub 45 of the gear wheel 40 is attached to the reduced end 44 of sleeve 39 through a pressed fit and abuts against the outer surface of plate 11 whereby the said sleeve is held from axial movement along staff 29.

The head 31 previously referred to is constructed with a radial surface 48 which serves as an abutment. In this surface are formed two notches 46 and 47 which serve as cams, the notch 46 extending partly through said head and the notch 47 extending completely through it. On the flange 37 is formed a finger 49 which may be constructed by severing a portion of said flange therefrom and pressing the same outwardly of the plane of said flange. The construction of this finger is best shown in Figs. 2 and 3. The corner 50 of this finger is adapted to ride along the abutment 48 and to enter into either of the two notches 46 and 47 when the portion 50 of said finger comes opposite the same. For urging the finger 49 against abutment 48 a compression coil spring 52 is utilized which is seated at one end against the inner surface of plate 11 and at its other end against the disk 38. By means of this construction the member 35 is driven at a uniform rate of speed from the gearing of the clock and at the same time is permitted to slide longitudinally of the

staff 29 to permit the finger 49 to follow the abutment 48 and to drop into notches 46 and 47. The finger 49 is constructed with a helical cam surface 53 which is adapted to engage the corner 54 formed on the flange 31 through the 5 notch 47 best shown in Fig. 3. This cam surface causes the member 35 to be moved in opposition to spring 52 whereby the finger 49 is moved from notch 47 back to the radial surface 48.

For cooperation with the trip mechanism of the clock I utilize two switches 55 and 56 which comprise three switch leaves 57, 58 and 59. These switch leaves are constructed with contacts 60, 61, 62 and 63 which are adapted to contact with one another to close circuits connected with said switch leaves. The switch leaves are mounted between insulating blocks 64, secured to the bearing plate 11 through screws 65. Screws 65 are insulated from the various switch leaves and contact may be had with the switch leaves through soldering lugs formed thereon and projecting outwardly beyond the insulating blocks. The two switch leaves 58 and 59 normally are spaced from one another as shown in Fig. 1 thereby maintaining the circuit therethrough open. The switch leaf 57, however, is normally sprung toward the right so that when this switch is without restraint the same brings the contacts of all three switch leaves together as shown in Fig. 2. This switch leaf is constructed with a finger 66 which rides against the radial surface of the disk 38. When this disk is shifted into the position shown in Fig. 1, switch leaf 57 is completely disengaged from the other switch leaves and all of the circuits through the switch leaves are open. When finger 49 enters notch 46 switch leaf 57 is so moved that the two contacts 60 and 61 are brought together. When the finger 49 becomes disposed in notch 47, switch leaf 57 is so moved that all of the contacts 60, 61, 62 and 63 are in contact, thereby closing all of the circuits through said switch leaves.

In Fig. 4 I have shown the wiring diagram of my invention. The line from which power is derived is indicated at B and comprises the two buses 67 and 68. The three switch leaves of the clock are designated by the same reference numerals and are illustrated in the wiring diagram in open position. Operating in conjunction with the clock is an alarm 69 which consists of a buzzer bell or similar acoustical device. In addition, a signal 70 is employed which has been illustrated as an electric lamp. These parts are connected to the switches 55 and 56 and to the line B as follows: A conductor 71 connects switch leaf 58 directly with the bus 67 of line B. Another conductor 72 connects the switch leaf 57 with one side of the lamp 70. 60 This lamp is further connected through another conductor 73 with the bus 68 of the line. One side of the bell 69 is connected through a conductor 74 with the other switch leaf 59 while the other side of said bell is connected through a conductor 75 with conductor 73. In addition to these various connections, a conductor 76 is employed which is connected to the bus 67 and which is further connected to a manually operated switch 77. This switch in turn is connected 70 through a conductor 78 with conductor 72 which leads to the lamp 70.

The operation of the invention is as follows: When the trip mechanism has been set through the alarm set 34 and the clock permitted to run, 75

the finger 49 travels about the abutment 48 on head 31. As soon as said finger reaches the notch 46 the same drops into the notch, shifting the disk 38 longitudinally along the trip staff 29. This brings the two contacts 60 and 61 together which completes a circuit. The circuit may be traced as follows: Commencing with bus 67 of line B, the circuit includes conductor 71, switch leaf 58, switch leaf 51, conductor 72, lamp 70 and conductor 73, which leads back to the opposite bus 68 of the line. The lamp 70 then becomes illuminated. As the finger 48 travels further the same drops into the notch 47. The position of the same when in said notch is illustrated in Fig. 2. In this position, all of the contacts of the switch leaves are connected together. When the parts are so disposed the circuit previously described remains closed and a new circuit is completed. This circuit can be traced as follows: Commencing with the bus 67 of line B, current flows through the conductor 71, switch leaf 58, switch leaf 59, conductor 74, the bell 69, conductor 75 and conductor 73, back to the other bus 68 of the line B. This causes the simultaneous operation of both bell and buzzer. The signal and alarm then continue to operate until the member 35 is raised through the cam 53 and the part 54 of head 31 and the various switch leaves reset to the position shown in Fig. 1. The length of time between operation of the signal 70 and the alarm 69 is determined by the circumferential extent of the notch 46 which can be determined in advance. The switch 77 and the conductors 78 and 76 form a shunt around the switch 55 by means of which the lamp 70 may be manually lit whenever desired. In the construction of the clock the said lamp is preferably situated on top of the clock or at such locality that part of the light emanating therefrom is directed upon the dial of the clock, whereby the time of day can be determined through the operation of said switch.

For the purpose of throwing off the alarm and preventing operation of the trip mechanism, a throw off device is provided which is indicated in its entirety by the reference numeral 79. This throw off device comprises a lever 80 which is pivoted through a pivot 81 to a bracket 82 secured to bearing plate 11 of frame 10. This bracket is attached to the said frame through screws 83 and projects across the said frame as best shown in Fig. 3. The lever 80 has formed on it an arm 84 which projects inwardly toward the staff 29. This arm is constructed at its end with a cam 85 having a spiralled cam surface 86 and terminates in a rounded tip 87. Cam surface 86 is adapted to engage the outer surface of the disk 38 and restrains the said member 35 from longitudinal movement along the staff 29, the amount of restraint of such movement being determined by the position of the said cam. In Fig. 1 the position of the cam when the member 35 is in operative position is shown in full lines while the position of the various parts when the cam is free from the disk 38 is shown in dotted lines. By means of this construction the alarm and signal can be shut off thereby preventing operation of either. When the lever 80 is in intermediate position disk 38 is so held that only the switch 55 is closed, whereby the lamp 70 may be permitted to function while the alarm 69 is cut off. In this manner, the signal lamp 70 may be operated or both the lamp and the alarm simultaneously actuated. By the use of a lamp for a signal it be-

comes unnecessary to immediately shut off the signal once the same is given. In this manner the sleeper may become fully aroused before he arises, thereby eliminating the shock usually encountered when the alarm is used instead of the signal. 5

My invention is highly advantageous in that a practical and useful device is provided whereby a signal may be used to arouse a sleeper instead of or together with an alarm. With my invention both signal and alarm may be employed and the same caused to be given at succeeding instances of time. My invention is positive in action and extremely accurate. Due to the fact that the same trip mechanism operates both switches, the exact timing of the signal and alarm can be accurately made so that the desired results can be procured with precision. By means of the throw off device either the signal or both signal and alarm can be given as desired or both completely cut out. With the manually controlled switch the signal may also be used to illuminate the clock dial whereby the time of day can be determined at all times.

Changes in the specific form of my invention, as herein disclosed, may be made within the scope of what is claimed without departing from the spirit of my invention.

Having described my invention, what I claim as new and desire to protect by Letters Patent is:

1. In combination, a clock including a frame, a staff carried by said frame, a member fixed relative to said staff, a member rotatable about the axis of said staff and slidable along said staff toward and from said first named member, one of said members being constructed with an abutment having two longitudinally extending notches therein, one of said notches being deeper than the other, means on the other of said members adapted to ride upon said abutment and to enter either of said notches, and means for urging said first named means in engagement with the abutment of said member. 35

2. In combination, a clock including a frame, a staff carried by said frame, a member fixed relative to said staff, a member rotatable about the axis of said staff and slidable along said staff toward and from said first named member, one of said members being constructed with a radial abutment having two longitudinally extending notches therein, one of said notches being deeper than the other, means on the other of said members adapted to ride upon said abutment and to enter either of said notches, and means for urging said first named means into engagement with the abutment of said member, a signal, an alarm and operating means operated by said revoluble member and adapted when said first named means is in one of said notches to operate said signal and when in the other of said notches to operate said alarm. 55

3. In combination, a clock including a frame, a staff carried by said frame, a member fixed relative to said staff, a second member revolvable about the axis of said staff and slidable along said staff toward and from said first named member, one of said members being constructed with a radial abutment having two longitudinally extending notches therein, one of said notches being deeper than the other, means on the other of said members adapted to ride upon said abutment and to enter either of said notches, means for urging said first named means into engagement with said abutment, two switches, 75

means operated by said revolute member for actuating said switches, said means operating when said first named means is disposed in one of said notches to actuate one of the said switches and when disposed in the other of said notches to actuate the other of said switches.

4. In combination, a clock including a frame, a staff carried by said frame, a member fixed relative to said staff, a second member revolute about the axis of said staff and slidable along said staff toward and from said first named member, one of said members being constructed with a radial abutment having two longitudinally extending notches therein, one of said notches being deeper than the other, means on the other of said members adapted to ride upon said abutment and to enter either of said notches, means for urging said first named means into engagement with said abutment, two switches, means operable by said revolute member for actuating said switches, said means operating when said first named means is disposed in one of said notches to actuate one of the said switches and when disposed in the other of said notches to actuate both of said switches.

5. In combination, a clock including a frame, a staff carried by said frame, a member fixed relative to said staff, a member rotatable about the axis of said staff and slidable along said staff toward and from said first named member, one of said members being constructed with an abutment having two longitudinally extending notches therein, one of said notches being deeper than the other, a finger on one of said members adapted to ride upon said abutment and to enter said notches, resilient means for urging said rotatable member toward said fixed member to hold said finger into engagement with said abutment, two switches including movable switch elements, and means operated by said

revolute member for holding said switch elements open when said finger is riding upon said abutment and for successively closing the switch elements of said switches when the finger successively enters said notches.

6. In combination, a clock including a frame, a staff carried by said frame, a member fixed relative to said staff, a member rotatable about the axis of said staff and slidable along said staff toward and from said first named member, one of said members being constructed with an abutment having two longitudinally extending notches therein, one of said notches being deeper than the other, means on the other of said members adapted to ride upon said abutment and to enter either of said notches, means for yieldingly urging said first named means in engagement with the abutment of said member, and a lever pivoted to said frame for shifting said rotatable member axially along said shaft to prevent engagement of the abutment with one of said notches.

7. In combination, a clock including a revolute member and a juxtaposed non-revolute member, one of said members being movable toward the other member, two switches, both operated by said movable member, two cams on one of said members and a follower on the other member adapted to engage said cams, said movable member occupying different positions when the follower is in engagement with the respective cams, said movable member when the follower is in engagement with one cam causing operation of one switch and when the follower is in engagement with the other cam causing operation of the other switch, and means for selectively holding said follower out of engagement with one of said cams to prevent operation of the switch controlled thereby.

CHRISTIAN E. SHOLDEN.
